UNITED STATES PATENT OFFICE.

WILLIAM T. MCLEAN, OF SIDNEY, OHIO.

EARTH-SCRAPER.

SPECIFICATION forming part of Letters Patent No. 242,348, dated May 31, 1881.

Application filed December 10, 1880. (No model.)

To all whom it may concern:

Be it known that I, WM. T. MCLEAN, of Sidney, in the county of Shelby and State of Ohio, have invented a new and useful Improvement 5 in Earth-Scrapers; and I do hereby declare the following to be a full, clear, and exact description of the same.

My invention is an improvement in that class of earth-scrapers the body of which is made of 10 thin sheet-steel with wooden back-board, the lower edge of which has always heretofore been secured to the scraper by means of rivets passing through the bottom of the scraper in such a manner that the rivet-heads soon wear off by 15 abrasion and let the back-board loose, which wholly disables the scraper for further use until repaired. Thus it will be seen that the means heretofore employed for securing the back-board to the bottom of the scraper are very 20 objectionable.

My improvement consists in the construction and arrangement of the devices for more perfectly securing the wooden back to the steel body without the use of said rivets, as and for 25 the purposes hereinafter more fully described.

In the accompanying drawings, forming a part of this specification, Figure 1 is a rear view of the scraper, and Fig. 2 a longitudinal section of the same.

30 A is the body, made of thin sheet-steel bent so as to form a convex bottom, and the sides bent up with a curve, in such a manner as to form nearly a quarter-circle between the convex bottom and the vertical sides.

35 B is the back-board.

D D is a double tie-rod passing through the upper part of the vertical sides, as shown in the drawings, and so constructed and arranged with screw-nuts and yoke as to form a loop at 40 each side of the scraper to embrace the handles E E, and through the medium of said handles press the sides of the scraper firmly against the back-board for the purpose of holding the

handles, the sides of the scraper, and the upper part of the back-board all rigidly in place. 45

F F are the vertical brace-straps riveted to the back-board, said brace-straps being bent so as to form loops, through which the tie-rods pass.

C is a tie-rod, placed near the lower edge of 50 the back-board, with each end passing through the sides of the scraper at or near the upper part of the curve or quarter-circle in the sides. This tie-rod is also provided with screw-nuts at each end, which bind the sides of the flexible 55 body against the back-board in such a manner as to hold the lower part of the back-board rigidly in place without the use of rivets.

In more clearly defining my claim, I will say I do not claim the tie-rod C as new; but when 60 placed near the lower edge of the back-board and passed through the sides of the scraper at or near the upper part of the curve, as herein-before described, it has a special function, in that it holds the lower part of the back-board 65 rigidly in place without the use of rivets, and also allows the back-board to be easily duplicated when worn out or broken, by taking out the tie-rods and inserting a new one, all of which can be accomplished simply by the aid 70 of a screw-wrench.

Having thus described my invention, what I claim as new, useful, and valuable, is—

In combination with the scraper A, back-board B, double tie-rods D D, and brace-straps 75 F F, the tie-rod C, when located near the lower edge of the back-board and passed through the sides of the scraper at or near the upper part of the curve or quarter-circle, for the purpose of holding the lower part of the back-board 80 in its place without the use of rivets, substantially as and for the purpose specified.

WM. T. MCLEAN.
